BILLIARD TABLE

Alfred F. Debicki, Muskegon, Mich., assignor to
 The Brunswick-Balke-Collender Company,
 Chicago, Ill., a corporation of Delaware

Application June 5, 1942, Serial No. 445,839

7 Claims. (Cl. 273—6)

This invention relates to billiard tables and it is particularly concerned with details of construction designed and devised to facilitate and simplify the final erection of the table.

One object of the invention is to provide a new and improved billiard table structure particularly adapted to be manufactured in units which can be assembled in the field, that is, at the location at which the table is to be used.

Another object of the invention is to provide a billiard table structure in which certain units of the supporting base are arranged to be bolted together, while additional units are adapted to be secured to the base structure by simple fastening means readily applied in the field without special tools or unusual skill.

It is also an object of the invention to provide a billiard table structure composed of units adapted to be prefabricated in the factory and to be assembled elsewhere and in which certain connections between the units are arranged with play or clearance so that slight inaccuracies in the manufacture shall not interfere with the successful assembly of the parts.

More specifically it is an object of the invention to provide a billiard table structure in which fastening elements are provided at fixed locations in the edges of the slate bed of the table, while the rails which are to be attached to said bed, are formed with elongated openings to engage such elements, with accommodation for inaccuracies in their location, and in which pocket supporting irons are also provided with elongated openings to engage fastening means extending from the rails after they are so mounted on the slate bed.

It is also an object of the invention to provide a table structure which can be conveniently assembled in the field by first setting up a base comprising legs connected by end panels and side panels and securing to such base the slate panels which constitute the table bed, then adding prefabricated side rail assemblies which include the cushions and top rails, securing such assemblies to the slate panels, then connecting the side rail sections by means of pocket-supporting irons, and finally applying the apron members which conceal the side rails—and utilizing the bolts or screws for all connections thus made in the erecting process, so as to facilitate the same and permit of its being accomplished in the field.

Other objects and advantages of the invention will appear from the following description taken in connection with the drawings, in which:

Figure 1 is a perspective view showing the legs

already connected by side and end panels to form a base structure and showing the slate panels which form the table bed with their under-frames in disassembled relation to the base but ready for application thereto;

Figure 2 is a vertical detail section showing one form of fastening means for connecting the under-frame to a slate panel;

Figure 3 is a perspective view showing the side rail assemblies arranged substantially in their final relative position to each other, ready for application to the table;

Figure 4 is a perspective view of the aprons similarly arranged in their final relative positions to each other;

Figure 5 is a perspective view showing a portion of one of the table legs and a portion of one side panel disconnected therefrom but ready for assembly therewith—certain parts being broken away or shown in section;

Figure 6 is a detail cross-sectional view on a large scale, taken as indicated at line 6—6 on Figure 12, showing the side rail assembly together with a portion of the apron and with fastening means securing the assembly to the slate and fastening means securing the apron to the side rail;

Figure 7 is a detail section taken substantially as indicated at line 7—7 on Figure 6;

Figure 8 is a horizontal detail section, on a large scale, taken substantially at line 8—8 on Figure 12;

Figure 9 is a horizontal detail section taken as indicated at line 9—9 on Figure 12;

Figure 10 is a detail perspective view of a pocket-supporting iron;

Figure 11 is a vertical sectional detail view similar to Figure 6 but taken at a different position along the side rail and indicating the method of installing the apron;

Figure 12 is a perspective view of the completed table.

While the invention is susceptible of various modifications and alternative constructions, the embodiments shown in the drawings and described hereinafter are by way of preferred illustration only and it is not intended that the invention be limited thereto or thereby; but it is the intention to cover all modifications and alternative constructions falling within the spirit and scope of the invention as defined by the appended claims.

Heretofore it has been the usual practice in the manufacture of billiard tables to substantially complete the fabrication and assembly of the

55

table as a finished unit substantially ready for use upon arrival at its destination. However such a unit is extremely heavy and bulky in shipment and is awkward to handle in placing it in position for use. It requires special care in packing to prevent damage in shipment and thus represents a considerable liability in transit. The present invention provides for the prefabrication or factory construction of sub-assemblies or units which may be separately packed and shipped to their destination, where they may be assembled into a completed table either by a mechanic in the field or by the customer himself and the means of assembly is such that, if necessary, the table can be easily taken apart and shipped to another point for re-erection if desired. Such a structure is particularly valuable for home use, since in many cases the basement playroom or other recreation room in which the table is to be set up has no doors or stairways large enough to accommodate a full size, fully assembled table, whereas the various sub-assemblies can be easily delivered to such a room and then combined into the complete table.

As shown in Figure 1 the base structure of the table consists of box-type legs 1, which are connected by side panels 2 and end panels 3. Figure 5 shows blocks 4 which are nailed and glued into each leg at its upper end and which are drilled at 5 to receive fastening bolts—a threaded, flanged, tubular nut 6 being secured in the lower end of each of the bolt holes 5. Similar tubular nuts 7 are set in two vertical walls of the leg 1. Figure 5 also shows one of the side panels 2 having block 8 permanently secured by nails and glued to its inner face at the end, with bolts 9 extending through the block 8 for engagement with the nuts 7 in the face of the leg 1. The side panel assembly includes a reinforcing member 11 secured along the lower edge of the side panel and a cap 12 secured to the upper edge extending outwardly from the outer face of the panel 2 and also extending beyond the end of the panel. The latter extending portion of the cap 12 is designed to rest upon the top of the leg 1 so that bolts 13 extending through the cap 12 may register with the nuts 6 in one of the blocks 4 of the leg for securing the cap firmly to the top of the leg.

Each of the end panels 3 is substantially similar to the side panels 2, with caps 14 of the end panels resting upon the legs 1 and secured thereto by bolts 15, as indicated in Figure 1. Each end panel includes blocks 16, with bolts 17 extending therethrough into the adjacent legs 1, and each end panel has a reinforcing member 18 along its lower edge.

Each of the legs is pre-fabricated at the factory and each of the side panel assemblies and end panel assemblies is similarly completed before shipment. Then the first step in the erection of the table consists in setting up the legs 1 on the floor in approximately their final positions and connecting them by bolting the side and end panels thereto.

The next step is to insert the cross-rails 20, which are shown in Figures 1 and 5 with their ends fitted into vertical grooves 21 in the side panels 2 and the caps 12, and resting upon pillow blocks 22 which are permanently fixed on the inner faces of the side panels. The cross-rails 20 are held in place by angle-brackets 23 connecting them to the side panel assembly.

The slate bed of the table is customarily made in three sections or panels 24 and each panel is

provided with a wooden under-frame 25. Preferably the under-frames will be secured to the under surfaces of the slate panels at the factory and one of them is so shown in Figure 1; the other two are shown disassembled from their slate panels merely for the sake of more clearly illustrating their construction. Each slate panel is secured to its under-frame by screws 26 disposed adjacent the outer margin of the panel, considering their final position in the table; but the margins at the edges 27 which are to abut each other when positioned in the table are attached by fastening means extending upwardly into the slate from the under frames, but not piercing the slate so as to produce any breaks in its upper surface which is to provide the playing bed of the table. Such fastening means may be of the type shown in detail in Figure 2 which represents a fibre tube 28 inserted in a bore in the slate 24 and containing a quantity of lead 29 into which a wood screw 30 extends from the under-frame 25. The screw tends to expand the lead as it cuts its own thread therein and thus slightly expands the tube 28, giving it a firm frictional grip on the slate.

With each of the bed panels thus fitted with its own under-frame, the panels are lowered onto the base structure which is shown in Figure 1 ready to receive them. Holes 31, previously drilled at the factory, to receive securing means for the panels, are utilized as guides for drilling registering holes in the caps 12 and 14, and long screws 32 set into these holes secure the bed panels to the base structure. The abutting marginal portions of the slate panels 24 with their under-frames 25 rest upon the cross-rails 20 and are supported thereby.

After the slate panels are thus placed in final position, the usual felt cover cloth 33 is applied over them and its marginal portions are secured to the under-frames 25 by means of tacks, as seen at 34 in Figures 6 and 11.

As shown in Figure 3, the cushions 35 are provided in association with sectional side rails 36 commonly called "blind" rails and having secured to them the top rails 37. The blind rail sections 36 are supported by attachment to the slate panels 24 of the bed, and to provide for such attachment the edges of the panels are drilled at the factory to provide them with bores 38 extending inwardly from their outer edges—that is, those edges which form the outlines of the table bed as a whole. A threaded sleeve 39 is fitted snugly into each of the bores 38 and the screws 26 which connect the slate 24 to its under-frame 25 intersects threaded tubes 39, thus anchoring the tubes in the slate. This arrangement is more fully described and is claimed in my Patent No. 2,333,709, dated November 9, 1943.

Bolts 40 extending through the blind rails 36 engage the threads of the tubes 39. These tubes thus serve as nuts for the bolts, whereby the bolts operate to clamp the blind rails 36 in position.

The cushions 35 and top rails 37, being permanently secured to the blind rails, are thus brought into final position in relation to the table bed. To allow for slight inaccuracies in the drilling of the holes 38 in the slate, and in the dimensions of the slate panels which are assembled in abutting relation to each other, the blind rails 36 are provided at the factory with slots or elongated holes 41 to receive the bolts 40, and since the rails 20 are spaced from each other at their ends to provide for the pockets of the billiard

table, each rail section may thus be positioned independently of the others and can be adjusted longitudinally within limits permitted by the length of the slots 41 without the necessity of any special cutting or fitting of the parts in the field.

When all the rails, with their cushion assemblies, have been mounted in position around the edges of the table bed, the pockets can be installed in the spaces between the rails. Each pocket assembly includes a pocket iron 45, such as that shown in perspective in Figure 10, having a web portion 46, lateral flange portions 47, and ears 48 by which it is secured to the blind rails for support. Figure 10 illustrates a supporting iron for a side pocket and this is shown in section in Figure 9, while Figure 8 shows a corresponding sectional view which includes the supporting iron 46 for a corner pocket. The corner pocket iron differs from the side pocket iron only in that the ears 49 have the corner pocket support extending obliquely from the side flanges 47 instead of at right angles as in the case of the side pocket. Each pocket iron includes an arm 50 extending upwardly from the web 45 and obliquely over the space in which the pocket itself is carried. Figure 8 shows a portion of a corner pocket 51, and Figure 9 shows a portion of a side pocket 52, and it may be understood that each of these pockets, which are preferably made of leather or like flexible material, is partially supported by a tab 70 which is attached to the overhanging oblique arm 50 of the pocket iron. This arrangement is more fully shown and described in my Patent No. 2,314,774, dated March 23, 1943.

In erecting the table it will usually be most convenient to secure the inner and upward edges of the pockets in place by tacks driven into the edges of the under-frames 25 before the pocket irons are added. Then with the pocket irons in position, the tabs 70 will be attached by screws to the overhanging arms 50, as more fully shown in my said co-pending application.

The ears 48 and 49 in the pocket irons are provided with elongated holes 53 for engagement with bolts 54 by which the irons are connected to the blind rails 36 crossing the gaps between adjacent ends of said rails. Preferably the blind rails 36 are provided with blocks 55, as shown in Figures 3, 8 and 9, permanently secured to their outer faces adjacent the ends of the rails, and the ears 48 or 49 of the pocket irons are secured against the faces of the blocks 55. Each blind rail is fitted with flanged, tubular nuts 56 extending into previously drilled holes in the rail and in the block 55, with their flanges entered through counter-bores 57 extending from the back of the rail. Thus the blind rails are prepared at the factory to receive the bolts 54 and any variation in the distance between bolts and adjacent nuts of the blind rails will be readily accommodated by the elongated holes or slots 53 in the ears of the pocket irons. Such variation may occur by reason of the adjustable mounting of the blind rails permitted by their slots 41, but in the final assembly the parts will be fitted snugly into proper relation to the slate table bed itself, with the cushions and pockets all properly positioned around the bed.

The blind rail is so named because it is hidden by apron members 60 extending around the table and shown in their assembled relation in Figure 4. The outwardly extending top rail 37 is formed with a groove 61 in its under surface to receive a positioning bead 62 on the upper

edge of the apron 60, as seen in Figure 6, and the apron is supported in position by means of a Z-iron 63 secured to the underside of the blind rail 36 by a bolt 64 and bearing upwardly against a rib 65 which is permanently glued and nailed to the under face of the apron 60. The end portions of the apron 60 are overlapped by wings 58 of an ornamental shield 59 associated with each of the pocket irons and the lower ends of the wings include horizontal flanges 58-a which extend under the lower edges of the apron 60 in its final position. This makes it necessary to introduce the apron upwardly in a tilted position, as indicated in broken outline in Figure 11, swinging it about the bead 62 as a fulcrum to bring its lower edges above the bottom flanges 58-a of the wings 58. The aprons 60 may be routed out at 66 for a short distance adjacent each end to permit the initial oblique positioning of the aprons indicated in Figure 11. Each of the bolts 64 engages a tubular nut 67 set into the blind rail 36, the rail being mortised at 68 to provide for insertion of these nuts. The Z-bar 63 is slotted at 69 to permit adjustment of the bar 63 to a final position, in which it supports the weight of the apron and also holds the apron in a vertical plane and in snug engagement with the wings 58 of the ornamental pocket irons so as to present a neat and pleasing appearance.

30 I claim:

1. In a billiard table, a hollow leg structure which includes four side walls secured together at their edges and blocks permanently secured to the inner faces of two adjoining side walls flush with their upper edges said blocks having vertical bolt holes and threaded nuts secured in said holes, two adjoining side walls having horizontal bolt holes with threaded nut elements secured therein, together with side and end panels, each 35 including a panel portion and a cap rail secured to the upper edge thereof and extending beyond the end of the panel portion, the extending end of said cap rail having bolt holes positioned to register with the vertical holes in a leg block, and 40 a block secured to the inner face of the panel portion flush with the end thereof and having horizontal bolt holes positioned to register with the horizontal holes in the wall of the leg.

2. In a billiard table, a blind rail, a top rail 50 secured thereto and extending outwardly beyond the outer vertical face of the blind rail, an apron disposed with its upper edge engaging the under side of the top rail, said apron having a downwardly facing shoulder on its inner face, and a 55 supporting member fastened to the blind rail and extending outwardly therefrom under said shoulder to support the apron.

3. In a billiard table, a blind rail, a top rail secured thereto and extending outwardly beyond 60 the outer vertical face of the blind rail, and having a longitudinal groove in its under surface, an apron having a bead on its upper edge engaged in said groove, said apron having a downwardly facing shoulder on its inner face, and a metallic 65 support fastened to the under side of the blind rail and extending outwardly therefrom under said shoulder to uphold the apron with its bead in the groove of the top rail.

4. In a billiard table, a blind rail, a top rail 70 secured thereto and extending outwardly beyond the outer vertical face of the blind rail, and having a longitudinal groove in its under surface, an apron having a bead on its upper edge engaged in said groove, said apron having a downwardly 75 facing shoulder on its inner face, and a

metallic arm fulcrumed at one end against the under side of the blind rail with its opposite end engaging said shoulder of the apron, together with a threaded member extending through an intermediate portion of said arm into the under side of said rail and adjustable to press the arm upwardly against said shoulder of the apron.

5. In a billiard table, a blind rail, a top rail secured thereto and extending outwardly beyond the outer vertical face of the blind rail and having a longitudinal groove in its under surface, an apron having a bead on its upper edge engaged in said groove, said apron having a downwardly facing shoulder on its inner face, a pocket fixture attached to the blind rail and having a wing positioned to lap over the outer face of the apron at the end thereof, a metallic arm fulcrumed at one end against the under side of the blind rail with its opposite end engaging said shoulder of the apron, said arm having a slot intermediate its ends, and a threaded member extending through said slot into the under side of said rail and engaging under the arm to press it upwardly against the shoulder of the apron, the outer end of said arm bearing against the inner face of the apron and the arm being outwardly adjustable within the range of its slot for pressing the apron outwardly into engagement with the wing of the pocket fixture.

6. In a pre-fabricated knock-down billiard table, leg units each having threaded bolt holes in two adjacent vertical faces and threaded bolt holes in a top face, end panels and side panels

having blocks flush with their ends with bolt holes to match those in the vertical faces of the legs and having cap rails extending to overlap the tops of the legs with bolt holes to match those in the top faces of the legs, bed panels with screw holes through their marginal portions directly over said cap rails and with threaded holes in their exposed edges, and blind rails to be attached to said edges of the bed with the ends of adjacent blind rails separated from each other to form pocket spaces, the end portions of said rails having threaded holes at fixed locations to receive fastening bolts for securing pocket irons bridging said spaces, and said rails having holes positioned to register approximately with the threaded holes in the bed and elongated longitudinally of the rails to compensate for the inaccurate location of the holes in the bed.

7. In a pre-fabricated knocked-down billiard table which includes a bed having threaded holes at intervals in its outwardly exposed edges, blind rails to be attached to said edges of the bed with the ends of adjacent blind rails separated from each other to form pocket spaces, the end portions of said rails having threaded holes at fixed locations to receive fastening bolts for securing pocket irons bridging said spaces, said rails having holes positioned to register approximately with the threaded holes in the bed and elongated longitudinally of the rails to compensate for the inaccurate location of the holes in the bed.

ALFRED F. DEBICKI.
